UNITED STATES PATENT OFFICE.

RALPH W. E. HAYES, OF GALVA, ILLINOIS, ASSIGNOR OF ONE-HALF TO HAYES PUMP & PLANTER COMPANY, OF GALVA, ILLINOIS, A CORPORATION OF ILLINOIS.

REDUCING-VALVE.

1,196,862.

Specification of Letters Patent.

Patented Sept. 5, 1916.

Application filed September 24, 1915. Serial No. 52,382.

To all whom it may concern:

Be it known that I, RALPH W. E. HAYES, a citizen of the United States, residing at Galva, in the county of Henry and State of Illinois, have invented certain new and useful Improvements in Reducing-Valves, of which the following is a specification.

This valve is intended primarily, though not exclusively, for use in connection with power spraying apparatus in which it is desirable to operate the engine and pump mechanism to a pressure capacity slightly in excess of that desired for spraying purposes, in order that an excess margin of power may be available at all times, so that the pressure of the spraying apparatus will always remain substantially constant and never fall below the desired degree.

The relief valve of the present invention is designed with a view of affording convenient means for quickly and certainly opening the valve when not in use to permit the passage of liquid without imposing a material pressure upon the engine and pump, and of such a nature that the valve elements may again be thrown into operative relation without readjustment of spring tension or other delicate manipulation.

The invention further relates to the means provided for quickly and easily assembling or disassembling the valve structure to permit cleaning or replacement of parts, and to the general structure and arrangement of the valve as a whole.

The invention further consists in the features of construction and combinations of parts hereinafter described and claimed.

In the drawings: Figure 1 is front elevation of the valve in its preferred form in working condition; Fig. 2 is a sectional elevation at right angles to the plane of Fig. 1, showing the valve in its inoperative position; Fig. 3 is a top view of the valve seat of Figs. 1 and 2; Fig. 4 is a perspective view of the cam block and lever for releasing the valve member from operative position; Fig. 5 is a front elevation of modified form of valve in its working condition; Fig. 6 is a sectional elevation of the valve of Fig. 5 at right angles to the plane of Fig. 5, showing the valve in its inoperative position; and Fig. 7 is a top or plan view of the valve seat of Figs. 5 and 6.

The valve of Figs. 1, 2, and 3, which is the preferred type of construction, consists

of a casing 7 having an intake nipple 8, and an outlet nipple 9, which nipples have threaded thereto the inlet and outlet pipes 10 and 11 respectively, arranged at right angles to one another. The bore of the nipple 8 is threaded to receive a valve seat 12 somewhat enlarged at its upper end 13, and provided around its upper margin with upstanding lugs 14 which are adapted to center a ball valve 15 which occupies a plane coincident with the center of the discharge pipe 11.

The casing 7 affords a valve chamber 16 which is closed at its upper end by means of a closing cap 17, which enters an annular recess 18 in the upper surface of the valve casing, and bears against a leather washer 19 entered in said recess. The parts are held in sealed relation by means of companion bolts 20 which are entered through companion lugs 21 and 22 on the valve casing and closing cap respectively, the bolts being tightened by means of nuts 23 which bear against the upper lugs 22.

The closing cap 17 is provided with a bore 24 which furnishes a mounting for a pressure rod 25 which, when the parts are in operating position, bears against the ball valve and serves to hold the same under spring tension against the ball valve to prevent the escape of spraying solution or other liquid, except by lifting the ball against pressure imparted by the rod. The spring tension is afforded by means of a coil spring 26 which bears against a cam block 27 rigidly secured by threading or otherwise to the upper end of the rod. The spring at its upper end bears against a disk 28 which furnishes a socket 29 for the rounded end 30 of an adjusting screw 31 threaded through the head end 32 of an arm 33 upstanding from the cap block 17.

The projecting upper end 34 of the adjusting screw is square to receive a wrench or other tool, and the parts are held in position for adjustment by means of a lock nut 35. The cam block 27 is provided on its under side with a diagonally extending wedge-shaped cam projection 36 which normally enters a cross-cut trough-shaped cam recess 37 in the upper face of the closing block 17. The cam head 27 is provided at one side with an outwardly projecting hand lever or grip 38 which permits turning of the cam head from the position shown in

Fig. 1 to that shown in Fig. 2, with the result that the cam projection 36 will be turned from a position in register with the groove 37 into a position in transverse relation thereto, thereby causing the cam 36 to ride up out of the groove 37 and lift the rod 25 against the tension of the spring 36, thereby relieving the ball from pressure and permitting it to rise and allow a practically uninterrupted circulation of spraying solution or other liquid. In order to provide a suitable bearing for the rod 25, a bushing 39 is entered into the under face of the cap block 17, in register with the bore therein, as shown in Fig. 2.

The valve of Figs. 5, 6, and 7 is quite similar to that previously described, except in respect to the means provided for retracting the pressure rod. It consists in a valve casing 40 provided with inlet and discharge nipples 41 and 42 to receive the inlet and discharge pipes 43 and 44 respectively. The valve seat 45 and ball valve 46 are substantially the same as the corresponding elements previously described. A cap block 47 is secured in place by means of bolts 48 entered through lugs 49 and 50 on the cap block and valve casing respectively, and essentially like those previously described. A pressure rod 51 entered through a bushing 52 serves, when the valve is in operation, to hold the ball under spring tension against its seat. A spring 53 surrounds the rod, and at its lower end bears against a disk 54 held in place by a cross pin 55 entered through the rod. The upper end of the spring bears against a traveling disk 56 provided at one side with an ear 57 which is entered into a vertically elongated slot 58 in an upstanding arm 59 which springs from the cap block 47 and terminates at its upper end in an over-hanging head 60, through which the pressure rod is entered.

The traveling disk 56 has entered therethrough an adjusting screw 61 having a square head 62 which bears against the under face of the over-hanging head 60, the relation of the parts being such that, when the adjusting screw is turned, the traveling disk being held against rotation will move up and down to regulate the compression of the spring. The upper end of the pressure rod is entered through a cam block 63 having handles 64 and a transversely extending wedge-shaped cam 65 on its lower surface. The cam block is held in position and rotative relative on the pressure rod by means of nuts 66. The wedge-shaped cam 65 cooperates with a cross-cut trough-shaped groove 67 in the upper surface of the over-hanging head 60, the relation of the parts being such that, when the cam head is turned in position, as shown in Fig. 5, the wedge-shaped cam will register with the groove 67, and when the cam head is turned at right angles thereto,

the cam will ride out of the groove and lift the pressure rod, thereby releasing the ball valve.

It will be noted from the foregoing description, that the valve of the present invention, in either of the forms described, is one which can be readily assembled or disassembled, and is one which can be thrown into and out of operative relation without disturbing the adjustment of the spring tension, or other careful manipulation. The relation of the parts is such that, when the pressure rod is lowered, the ball will support the entire tension of the spring, and in order to insure this result, it is desirable to cut the cam groove sufficiently deep, so that there will be a slight clearance between the wedge-shaped cam and the groove when the parts are in register, thereby throwing the entire load of the spring on the ball and supporting none of it on the cam elements.

I claim:

1. In a reducing valve, the combination of a casing provided with inlet and discharge passages, a valve seated within the casing, a cap block for the casing provided in its outer surface with a cam groove or channel, a pressure rod entered through the cap block and normally bearing against the valve member, a cam head provided with a cam adapted to register with said groove or channel, or to be turned out of register therewith for retracting the pressure rod to release the valve member, a spring exerting pressure on the cam head and pressure rod, means for adjusting the pressure of the spring, and a member upstanding from the cap block and adapted to receive the thrust of the spring adjusting means, substantially as described.

2. In a pressure reducing valve, the combination of a casing provided with inlet and discharge passages, a valve member seated within the casing, a pressure rod normally bearing upon the valve member, a cap block through which the pressure rod is entered, and provided with a cross-cut cam groove or channel, a cam head receiving the upper end of the pressure rod, and provided with a transversely extending cam and adapted to register with the groove or channel, a lever piece outwardly projecting from the cam head for turning the same, a spring bearing against the cam head, means for adjusting the pressure of the spring, and an upstanding member for receiving the thrust of the spring adjusting member, substantially as described.

3. In a pressure reducing valve, the combination of a casing provided with inlet and discharge passages, a valve member seated within the casing, a pressure rod normally bearing upon the valve member, a cap block through which the pressure rod is entered, and provided with a cross-cut cam groove or

channel, a cam head receiving the upper end of the pressure rod and provided with a transversely extending cam and adapted to register with the groove or channel, a lever 5 piece outwardly projecting from the cam head for turning the same, a spring bearing against the cam head, a screw for adjusting the pressure of the spring, and a standard 10 upstanding from the cap block and provided with an over-hanging head through which the screw is threaded, substantially as described.

4. In a pressure reducing valve, the combination of a casing provided with inlet and 15 discharge passages, a valve member seated within the casing, a pressure rod normally bearing upon the valve member, a cap block through which the pressure rod is entered, a standard upstanding from the cap block

and provided with an overhanging head, a 20 spring interposed between the overhanging head and the cap block for exerting a downward pressure on the pressure rod, adjustable means bearing against the spring 25 adapted to regulate the pressure on the pressure rod, and rotatable means connected with the rod and independent of the spring adjusting means, and including a cam co-acting with a suitably positioned fixed cam surface for imparting longitudinal movements to the pressure rod to raise or depress the rod in opening and closing the valve, 30 substantially as described.

RALPH W. E. HAYES.
